CLAIM

The ornamental design for a box planter, as shown and described.

DESCRIPTION

FIG. 1 is a front perspective view of a box planter showing our new design;

FIG. 2 is an isometric view thereof, the other corners being identical thereto;

FIG. 3 is a top plan view thereof, the bottom view being a mirror image thereof; and,

FIG. 4 is a side view thereof, all other side views being identical thereto.

FIG. 1

FIG. 2

FIG. 3

FIG. 4
